United States Patent Office

Des. 194,474
Patented Jan. 29, 1963

194,474

COMPARTMENTED TRAY OR THE LIKE

Marten Gottsegen, Chicago, Ill., assignor to Gotham Industries, Inc., Chicago, Ill., a corporation of New York

Filed Jan. 16, 1962, Ser. No. 68,323

Term of patent 14 years

(Cl. D44—10)

FIG. 1

FIG. 2

FIG. 3

FIG. 4

FIG. 5

FIG. 1 is a top plan view of a compartmented tray or the like embodying my new design;

FIG. 2 is a side elevational view thereof;

FIG. 3 is a similar view from the opposite side thereof;

FIG. 4 is an end elevational view thereof; and

FIG. 5 is a similar view from the opposite end thereof.

I claim:

The ornamental design for a compartmented tray or the like, substantially as shown.
